UNITED STATES PATENT OFFICE

161,689

FARE COLLECTION BOX OR SIMILAR ARTICLE

Max L. Grant, Providence, R. I.

Application August 4, 1950, Serial No. 11,591

Term of patent 14 years

(Cl. D52—4)

To all whom it may concern:

Be it known that I, Max L. Grant, a citizen of the United States of America, residing at 90 Hazard Street, in Providence, county of Providence, and State of Rhode Island, have invented a new, original, and ornamental Design for a Fare Collection Box or Similar Article, of which the following is a specification, reference being had to the accompanying drawing, forming a part thereof.

Fig. 1 is a perspective view of a fare collection box embodying my design;

Fig. 2 is a right-hand end elevation of the fare box shown in Fig. 1, the pedestal being broken away;

Fig. 3 is a plan view of the fare box shown in Fig. 1; and

Fig. 4 is a fragmentary rear view of the upper part of the fare collection box.

I claim:

The ornamental design for a fare collection box or similar article, substantially as shown.

MAX L. GRANT.
